COOKER

Robert W. Thomas, Wichita, Kans., assignor to William D. De Vore and R. A. De Vore, Wichita, Kans.

Continuation-in-part of design application Ser. No. 196,254, Nov. 5, 1971, now Patent No. 229,625. This application Feb. 12, 1973, Ser. No. 331,544

Term of patent 14 years

Int. Cl. D7—02

U.S. Cl. D7—94

FIG. 1 is an elevational view of a cooker showing my new design;

FIG. 2 is a top perspective view of same from the side opposite that seen in FIG. 1;

FIG. 3 is an elevational view of a modification of the cooker of FIG. 1 wherein the lower support legs have been shortened and angled outwardly;

FIG. 4 is a top perspective view of the latter from the side opposite that seen in FIG. 3;

FIG. 5 is a bottom plan view of FIG. 3; and

FIG. 6 is a top plan view of FIG. 3.

The bottom plan and top plan views of FIG. 1 are somewhat similar to those of FIGS. 5 and 6.

This application is a continuation-in-part of design application Ser. No. 196,254, filed Nov. 5, 1971, and now Pat. No. D. 229,625, dated Dec. 18, 1973.

I claim:

The ornamental design for a cooker, substantially as shown and described.
